United States Patent Office

Des. 196,986
Patented Nov. 26, 1963

196,986

COMBINED BOTTLE AND CLOSURE

Philip B. Schnering, Stevenson, and Harvey B. Weeks, Jr.,
Towson, Md., assignors to McCormick & Company,
Incorporated, Baltimore, Md., a corporation of Maryland

Filed Apr. 16, 1963, Ser. No. 74,458

Term of patent 14 years

(Cl. D58—9)

Fig. 1.

Fig. 2.

Fig. 3.

Fig. 4.

The rear and side elevations not shown are like the elevations shown in FIGURES 1 and 2.

We claim:

The ornamental design for a combined bottle and closure, as shown and described.
